TAPE CASING

Filed Jan. 29, 1926

FIG. 1

FIG. 2

FIG. 3

FIG. 5

Inventor
NATHAN H. SHILLMAN

By
Leon Edelson
Attorney.

UNITED STATES PATENT OFFICE.

NATHAN H. SHILLMAN, OF BALTIMORE, MARYLAND.

TAPE CASING.

Application filed January 29, 1928. Serial No. 34,563.

This invention relates to casings for measuring tapes and more particularly to casings for use in connection with that type of thin steel graduated tape adapted to be wound on a drum in the casing for use in sounding the depth of tanks, wells and the like containing oil or similar liquids, and for general use in the field.

In sounding oil tanks or tanks containing similar liquids and in all field work there is necessarily left a film of oil or moisture or other such deposit on the tape line. Not only does this result in an unclean tape quickly susceptible to rust and defacement of the graduation marks, but it also results frequently in broken tapes. To avoid these unsatisfactory conditions it becomes necessary to wipe the tape as it is drawn into its casing or frame. Heretofore it had been the practice to so wipe the tape as it is drawn in a few feet at a time. This, however, proved cumbersome and entirely unsatisfactory both from the point of speed as well as efficiency. As a result a casing such as is described in the applicant's Patent 1,485,634, March 4, 1924, was developed. The present application is for improvements in the patented structure.

Accordingly, the principal object of this invention is the provision of a casing which, while it is adapted to completely house the tape, at the same time facilitates ready removal and replacement of the tape or any part of the interior structure of the casing.

A further object of the invention is the provision of an improved rotary crank and winding drum detachably mounted within the casing and adapted to have wound thereon the measuring tape.

A still further object of the invention is the provision of an improved wiping means for cleaning the tape as it is wound upon the crank element, this wiping means taking the form of a stuffing box arranged at the entrance into the casing.

A still further object is the provision of a pair of wiping blocks arranged for relative adjustment toward and away from each other by means of which a greater or less degree of pressure may be imparted to the tape as it passes between them, thus assisting not only in the wiping process but also materially effecting a braking action on the tape to preclude a too rapid winding where-by there is insured a uniform tension on the tape as it is wound upon the winding drum.

A still further object is the provision of an improved form of retaining means in the nature of a yoke for maintaining the separable parts of the casing in closed position. 60

A still further object is the provision of an improved handle for the casing, this handle being pivotally secured at the hinged end of the casing and adapted to be securely held in position by means of the yoke embracing the entrance to the casing. 65

Other objects of this invention will appear more fully hereinafter.

The invention consists substantially in the construction, combination, location and relative arrangement of parts, all as will be more fully hereinafter set forth, as shown in the accompanying drawings, and finally pointed out in the appended claims. 70

In the accompanying drawings: 75

Figure 1 is a longitudinal section of the device showing the relative arrangement of the casing, the winding drum to which the tape is attached and the wiping blocks.

Fig. 2 is a top view of the device with a part of the casing removed to show the manner of seating the crank element and winding drum therein. 80

Fig. 3 is a view of the entrance end of the casing, part of the handle being broken off. 85

Fig. 4 is a view in perspective of the casing elements including the locking yoke and the handle.

Fig. 5 is a view in perspective of the rotary crank element and the winding drum. 90

The same part is designated by the same reference numeral whenever it occurs throughout the several views.

A characteristic feature of the device is that the casing can readily be opened or closed and the component parts easily taken apart and then reassembled. No tool other than a screw driver or other similar device is necessary to accomplish this. The casing is constructed in two halves, substantially 95 duplicates, which are closed diametrically to form the whole, this being effected by hinging the two halves at one end and by the provision of a yoke and set screw locking device at the other end. The casing has a central opening, forming two bearings of unequal diameters, in which is seated the rotary crank element and the winding drum. 100 105

It is to be noted as of particular moment in this case that the rotary crank element and the winding drum are mounted one upon the other in such manner that they con-

stitute one single element of the complete device. That is, the winding drum proper is rigidly and permanently secured upon the rotary crank element by means of spacers 6 projecting from the body of the crank element whereby there is attained a winding drum of a diameter sufficiently great to prevent a too abrupt winding of the inner end of the tape and yet providing for a minimum weight of the rotating part of the device by reason of the reduction so made possible in size of the casting or machined element, as the case may be.

The improvement in the stuffing boxes is 15 also of paramount importance. By reason of the improved arrangement wherein is used a pair of opposed Babbitt metal, graphite or other non-abrasing blocks a positive wiping and cleaning action is assured. 20 Sockets are formed integrally in the opposing faces of the casing at the entrance end thereof for the reception of these blocks, these sockets being each provided with set screws in the bases thereof for positive adjustment 25 of the blocks relatively with respect to each other to vary the degree of pressure desired to be had upon the tape.

Referring specifically to the drawings it 30 will be seen that the casing consists primarily of two members indicated generally by the reference characters 10 and 11. These members 10 and 11 are each of substantially semi-circular outline having hollow interiors 12 and 13 such that when assembled together 35 with their complementally formed edges in engagement with each other a closed casing is provided in which may be accommodated the measuring tape 14, shown in Fig. 1. At the rear end of the members 10 and 11 are 40 provided dovetailed hinge-pin bosses, 15 and 16, respectively, through which extends a hinge pin 17, thus providing a hinged joint at this end of the casing. At the front or entrance end of the casing the members 10 45 and 11 have integrally formed therein inwardly projecting portions 18 and 19, these portions being in turn provided with recesses or sockets 20 and 21, respectively, for a purpose to be presently described.

Hinged to one of the casing members, 50 preferably to the member 11, at the extreme forward end thereof is a yoke 22 of generally U-shape, the legs and base of the U being adapted, when swung from the position 55 shown in dotted lines in Figure 1 rearwardly, to embrace the entrance ends of the casing members. By means of the set-screw 23 passing through the base of the yoke 22 and engaging the upper surface of the casing, the members 10 and 11 are locked firmly 60 into closed position, in the manner particularly shown in Figures 1 and 3.

Each of the casing members 10 and 11 is 65 provided with enlarged semi-circular bosses 24 and 25 which, when the members are

locked together, constitute bearings on opposite sides of the casing in which are seated the respective ends of the journal of the winding drum, which latter will be described hereinafter. In this particular instance the 70 bearing 24 is of greater diameter than the bearing 25, though for the purposes of this invention these bearings could well have been of equal diameter. As is best apparent in Figures 1 and 3 the entrance ends of casing members 10 and 11 are complementally notched to form a slightly flared opening 26 to provide for an easier entry of the tape 75 into the casing.

The rotary crank unit 27 which is preferably in this instance a part of the winding drum is shown in perspective in Figure 5. This unit consists essentially of a large journal 28 formed integrally with a smaller journal 29, these journals being adapted to fit 80 respectively in the bearings 24 and 25 in the casing. Formed intermediately of journals 28 and 29 is an enlarged central portion 30 having formed therein depression 31 between the side walls of which is adapted to 85 extend a small pin 32 for attachment thereto in any suitable manner of the inner end of the tape 14. Projecting radially from the exterior surface of the central portion 30 of the crank unit are a plurality of spacers 33 90 to the free ends of which is secured in permanent fashion preferably a split annular member 34. One end 35 of this member 34 is inwardly offset with respect to the other thus providing a slot 36 through which the 95 inner end of the tape 14 may pass for securing to the pin 32. (See Figure 1.)

To prevent lateral displacement of the crank unit with respect to the casing integrally formed flanges 37 and 38 are provided 100 at the opposite ends thereof, these flanges embracing the exterior surfaces of the bearings 24 and 25, respectively, when the crank unit is positioned within the casing. Preferably formed integral with the flange 37 is 105 a lateral extension 39 to which is pivoted the crank arm 40. This arm 40 is provided with a handle 41 adapted to seat, when folded out of use, within a socket 42 provided therefor in the body of the crank unit.

The stuffing box is formed integrally at the entrance end of the casing by the provision of the oppositely disposed sockets 20 and 21 in each of which is disposed a wiper element 43. These wiper elements are preferably formed of Babbitt metal, graphite or some similar non-abrasing material and are arranged by any suitable method to fit snugly within their respective sockets 20—21. Set screws 44 and 45 passing through the 110 base walls of the sockets from the exterior surfaces of the casing provide a suitable means for projecting the wiper elements outwardly from their sockets into wiping engagement with the opposite surfaces of the 115 120 125 130

tape as the latter passes into the casing through the entrance opening 26 to be wound upon the drum. When the tape is not in use, the wiper elements, due to the pressure exerted upon the tape act as a brake thereon, thus preventing any unintended unwinding.

A handle 46 is provided for the casing, this handle extending substantially from the pivoted end to the entrance end thereof and the main body portion being spaced therefrom a distance sufficient to readily accommodate the fingers. One end 47 of the handle is mounted directly upon the pivot pin 17 while the other end 48 is provided with a projecting tab 49 adapted to overlie the meeting edges of the casing members at one side thereof. The locking yoke 22 is formed with an offset portion 50 adapted to embrace the tab 49 when the casing is locked and ready for use.

By reason of the construction described it will be seen that a tape casing has been provided which may be readily and conveniently opened in the manner particularly shown in Fig. 4 for the insertion or removal of the crank and winding drum unit. Thus all of the elements comprising the device are readily available for purposes of clearing and adjustment. Further an arrangement of wiping elements has been provided which not only effectively cleans the tape as it is wound upon the winding drum but it also prevents the entry of any foreign substances into the interior of the casing. Still further, these same wiping elements constitute an effective brake on the tape with the result that a frequent cause of breaks is eliminated.

It is to be understood that various arrangements and modifications other than that described above may be devised, and yet come within the spirit of this invention. Accordingly, it is the intention that the appended claims be construed broadly to cover such alternative arrangements and modifications.

What is claimed as new and useful is:

1. A tape holding device comprising a pair of diametrically opposed substantially similar members adapted when fitted together to form a housing for a tape, integral bearing bosses of unequal diameters disposed centrally of said members and a rotating element carried by said bearings on journals seated in said bearings, the inner walls of said bearings being provided with grooves for receiving a lubricant.

2. A winding drum for a measuring tape

or the like comprising a central body, a plurality of spacing elements projecting radially from the surface of said body, and a split annular member secured rigidly to the free ends of said spacing elements, the adjacent ends of said annular member being relatively offset with respect to each other to accommodate the end of the measuring tape. 60

3. A winding drum for a measuring tape or the like comprising a central body, a winding surface spaced from and rigidly secured 70 to said body, means in said body for securing thereto of the inner end of the tape, said winding surface being provided with means for permitting free access to said securing means. 75

4. A winding drum for a measuring tape or the like arranged to be removably received within a tape casing as a unitary assembly and comprising a central body having reduced oppositely projecting portions, 80 said portions being integral with said body and forming journals for said drum, and annular flanges at the outer extremities of said journal portions for preventing lateral displacement of the drum when in assembled 85 position in its casing.

5. In a tape holding device, a pair of diametrically opposed similar members adapted when fitted together to form a casing for a tape, a hinge pin passing through adjacent 90 ends of said members to effect a hinged connection therebetween, and a handle for said casing having one end thereof also hingedly mounted upon said hinge pin. 95

6. A tape casing comprising a pair of 95 complementally formed members adapted when fitted together to form a casing for the tape, a handle for said casing of a length substantially equal to that of the casing and having its main body portion spaced therefrom, the adjacent ends of said members and handle being hinged together, and a yoke pivotally connected to the free end of one of said members and adapted to commonly embrace the free ends of said other member 100 and said handle whereby to lock the same together. 105

7. A tape casing comprising a pair of complementally formed members adapted when fitted together to form a casing for a tape, 110 a handle for said casing, said members and handle being hinged together at adjacent ends thereof and arranged to be locked together by a means embracing the free ends of said members and handle, said means having a portion thereof offset to accommodate the free end of said handle. 115
